UNITED STATES PATENT OFFICE.

WALTER W. SCHULTZ, OF RICHMOND, INDIANA, ASSIGNOR TO THE WAYNE WORKS, OF SAME PLACE.

CARRIAGE-POLE.

SPECIFICATION forming part of Letters Patent No. 614,767, dated November 22, 1898.

Application filed April 8, 1898. Serial No. 676,945. (No model.)

To all whom it may concern:

Be it known that I, WALTER W. SCHULTZ, residing at Richmond, in the county of Wayne and State of Indiana, have invented certain new and useful Improvements in Carriage-Poles, of which the following is a specification.

The object of my invention is to improve the method of combining a doubletree to a vehicle-pole, so as to make a stronger and more reliable device.

The features of my invention are more fully set forth in the description of the accompanying drawings, making a part of this specification, in which—

15 Figure 1 is a plan view of a vehicle-pole and doubletree with my improvements attached. Fig. 2 is a section on line *x x* of Fig. 1. Fig. 3 is a modification of Fig. 2. Fig. 4 is a modification of the curved stop-brace shown in Fig. 1.

A represents a carriage-pole; B, the doubletree, hinged thereto by bolt C.

D represents the bow for attaching the pole to the axle.

25 E represents the draw-iron, attached to the pole and bow. It is preferably of T-form, as shown at *a*, Fig. 1, and it is secured to the tongue and bow by bolts *b*.

F represents a stop-brace. It is made of 30 semicircular form and passes under the arch *c*, formed in the draw-iron, as shown in Fig. 2.

G represents a stop-bolt passing through the draw-iron and through the pole.

The brace-stop I have shown as constructed 35 in either of two ways, each the equivalent of the other. In Fig. 1 segmental slot *d* is pro-

vided centrally in the brace. In Fig. 4 the stop is formed by an offset *e*, formed in the middle of the brace. The shoulders *f* serve as stops to limit the movement of the brace, 40 thereby limiting the movement of the doubletree.

In order to cushion the movement of the brace-stop through the arch of the draw-iron and to take up lost motion, I provide the following devices:

g represents a recess formed in the pole vertically under arch *c*. *h* represents a coil-spring seating in the bottom of said recess and against the washer *i*, which bears against 50 the under side of the stop-brace. The stop-brace does not bear upon fastening-bolt *G*, but passes freely around same. This stop-brace performs the same office as stay-chains, but it is superior in strength and is neater 55 and more desirable, and at the same time it braces and supports the doubletree.

Having described my invention, what I claim, is—

In combination with a pole and doubletree 60 of a vehicle, the stop-brace *F*, the draw-iron *E* provided with a notch *c* and the cushioning-spring *h* adapted to bear on the under side of the stop-brace, substantially as specified.

In testimony whereof I have hereunto set 65 my hand.

WALTER W. SCHULTZ.
